WIRE NETTING MACHINE

Theodor Rössler, Neustadt (Orla), Germany

Application November 4, 1937, Serial No. 172,746
In Germany May 8, 1936

10 Claims. (Cl. 140—112)

This invention relates to wire netting machines and more particularly to a machine for forming wire netting wherein the weft or transverse wires are welded to the warp or longitudinal wires.

5 An object of this invention is to provide a machine for making of wire netting wherein the weft or transverse wires are tensioned during the welding operation so that the mesh formed by the weft and warp wires will be evenly spaced 10 apart and are relieved of slack or bends so that a smooth mesh is formed by the machine.

Another object of this machine is to provide a plurality of reciprocating shuttles or wire tensioning members which are adapted to periodically place the weft wire upon the warp wires, the weft wire being welded to the warp wires and subsequently released from the shuttles so that a substantially continuous movement of the machine may be effected.

20 A further object of this invention is to provide pairs of reciprocating shuttle members which are mounted for rotation on a shuttle carrier in a manner whereby any desired number of shuttles may be used depending only upon the size of the mesh desired.

25 With the foregoing and other objects in view, the invention will be more fully described hereinafter, and will be more particularly pointed out in the claims appended hereto.

30 In the drawings, wherein like symbols refer to like or corresponding parts throughout the several views:

Figure 1 is a detail front elevation partly in vertical section of a wire making machine constructed according to an embodiment of this invention.

Figure 2 is an enlarged longitudinal section partly broken away taken on the line 2—2 of Figure 1.

40 Figure 3 is a sectional view taken on the line 3—3 of Figure 1.

Figure 4 is an enlarged vertical section partly in detail of the releasing means for one of the shuttle members.

45 Figure 5 is a fragmentary perspective view of the wire mesh formed by this machine.

Referring to the drawings wherein like numerals designate corresponding parts throughout the several views, the numeral 10 designates generally a pair of standards having bearings 13 at their upper ends in which a drive shaft 11 is journaled. A drum generally designated as 12 is fixedly secured on the drive shaft 11 and comprises a pair of spaced apart plates 14 and 15. A second drum generally designated as 17 is

fixed to the drive shaft 11 in spaced relation to the drum 12 and comprises spaced apart plates 18 and 19.

A welding structure generally designated as 21 is disposed between the two drums 12 and 17 and 5 is supported from a frame structure 22. The welding structure 21 is adapted to be vertically moved into engagement with the weft and warp wires at intervals by a mechanism not shown. As shown in Figure 3, the warp wires 23 are trained 10 over a guide bar 24 which is preferably stationary and may be secured in any manner to the frame structure 22. The warp wires are drawn horizontally from the guide bar 24 through the electrodes 21, the pulling or drawing means for the 15 warp wires 23 being of any suitable structure, not shown.

The drum 12 has a plurality of shuttle members 25 slidable in the end plates 14 and 15, and these shuttle members 25 are adapted to move in 20 a direction parallel with the shaft 11 simultaneous with the rotation of the drum 12 and the shaft 11. Reciprocation of each shuttle member 25 is effected by means of a stationary shuttle operating member 26 which is provided with a 25 cam groove 27 in which a roller 28 carried by the shuttle member 25 is adapted to engage. The shuttle member 25 comprises an elongated bar 29 which is provided with a longitudinally extending channel 30 therein as shown in Figure 2. 30 The forward end of the shuttle member 25 is reduced as at 31 and a sleeve or wire guide member 32 is positioned in the nose or forward end of the shuttle member 25. A wire supply reel or drum 33 is provided for each shuttle member 35 25 and is rotatably supported by bracket members 34 secured to the plate 14. The reel or supply member 33 as shown in Figure 1 is positioned between the two plates 14 and 15 of the drum 12. The wire taken off of the reel 33 is threaded between a plurality of tensioning rolls 35 which are carried by the bar 29 in the groove or channel 30. The wire 36 taken from the supply reel 33 is then passed beneath a holding or gripping member 37 in the form of a toothed disk which is 45 eccentrically mounted on a pin 38. A spring 39 is secured at one end to a wall of the groove 30 and at the other end to the gripping member 37 and constantly holds this member 37 in engagement with the wire 36.

50 The drum 17 has a plurality of shuttle members 40 which are slidable in the plates 18 and 19, and these shuttle members 40 comprise an elongated bar 41 having at their inner ends a pair of wire clamping or gripping members 42. 50

The drum 17 has a plurality of shuttle members 40 which are slidable in the plates 18 and 19, and these shuttle members 40 comprise an elongated bar 41 having at their inner ends a pair of wire clamping or gripping members 42. 50

The gripping members 42 are rockably mounted on pins 43 and their gripping faces are preferably serrated as shown in Figure 2 so that the wire gripped therebetween will be firmly held against movement. The clamping members 42 are mounted within a channel or slot 44 provided in the forward end of the bar 41. An operating rod 45 for the clamping members 42 is slideable in a bore 46 provided in the rod 41 and the forward end of the rod 45 is connected to the clamping members 42 by means of a pair of oppositely extending links 47 so that movement of the rod 45 in one direction will move the clamping members 42 into released or open position. A spring 48 is positioned in a bore 49 provided in the outer end of the rod 41 and the inner end of the spring 48 engages against a ring or collar 50 secured to the rod 45. The outer end of the spring 48 engages against a bearing 51 mounted in the rod 45.

A stationary shuttle operating member 52 is secured to the adjacent standard 10 and is provided with a cam groove 53 in which a roller 54 secured to each shuttle member 40 engages. An arm or bracket 55 is secured to each shuttle member 40 and a lever 56 is rockably mounted on the arm 55 and is provided at one end with a roller 57 which is rotatable thereon and which is adapted in one position to engage a stationary member 58 which operates to move the rod 45 outwardly and thereby swing the wire clamping members 42 into a released position. The opposite end of the lever 56 is provided with a fork 59 having rollers 60 engaging in a grooved or channeled member 61 secured as by nuts 62 to the outer end of the rod 45.

A second releasing member 63 is secured to a slideable rod 64 carried by guide members 65. The bar 64 is preferably provided with teeth 66 which are engaged by a toothed wheel 67 mounted on a shaft 68. The shaft 68 is periodically dropped by means of an arm 69 connected to a rod 70 having a roller 71 which engages a cam member 72. The cam member 72 is mounted on a shaft 73 connected to a suitable part of the mechanism herein disclosed and so timed that when the two shuttle members are at their outermost position, as shown in Figure 1, the releasing member 63 will be moved inwardly at substantially the same time that the welding means 21 is moved into operative position.

In the use and operation of this machine, the drive shaft 11 is rotated by any suitable driving means and the weft wire 36 is initially threaded through the nose 32 of the weft bar 25. The weft wire 36 is preferably disposed with the end thereof projecting slightly beyond the nose 32 so that when the two shuttle members 25 and 40 are at their lowermost position, these two members will have their inner ends in substantially contacting relation, as shown in Figures 1 and 2. In this position the releasing member 58 will engage the roller 57 so as to move the rod 45 outwardly or to the left and thus swing the wire gripping members 42 into wire receiving position. At this time both of the drums 12 and 17 are rotating together and when the roller 57 passes off of the releasing member 58, the spring 48 will move the rod 45 inwardly to constantly maintain the clamping members 42 in clamping position about the end of the wire. As the two drums 12 and 17 continue their rotation in unison, the cam grooves 21 and 53 will move the shuttles 25 and 40, respectively, 75 away from each other. During the movement of

the shuttle members 25 and 40 away from each other, the pulling shuttle 40 will draw the wire 36 through the shuttle 25 and the tensioning rollers 35 will maintain this weft wire in tensioned condition at all times. When the shuttle members 25 and 40 are at their outermost and, in the present instance, at their uppermost position, the weft wire 36 is brought into contacting relation with the warp wires 23 and at this time the welding means 21 is brought into contacting relation with the warp 23 from below and with the weft 36 from above. At this time, the weft 36 is cut off by means of a pair of shears 74 which leave a small projecting portion of the wire 36 projecting beyond the inner end of the shuttle member 25. Simultaneous with the cutting off of the weft wire 36, the cam 72 moves the releasing member 63 to the right so as to open the clamping members 42. The two drums 12 and 17 thereafter continue their rotation and the shuttle members 25 and 40 gradually move toward each other until they reach the lowermost position at which time the inner ends of the shuttle members 25 and 40 are in a wire transferring position, as shown in Figure 2.

It is obvious that various changes and modifications may be made in the details of construction and design of the above specifically described embodiment of this invention without departing from the spirit thereof, such changes and modifications being restricted only by the scope of the following claims.

What is claimed is:

1. A wire netting machine comprising a pair of shuttle members, rotatable mounting means for said shuttle members, and stationary means engageable with said shuttle members to effect reciprocation of said shuttle members coactive with the rotation thereof.
2. A wire netting machine comprising a pair of shuttle members, means supporting said shuttle members in alinement, means for rotating said supporting means, and means engageable with said shuttle members to effect reciprocation thereof coactive with the rotation of said supporting means.
3. A wire netting machine comprising a pair of shuttle members, means supporting said shuttle members in alinement, means for rotating said supporting means, means engageable with said shuttle members to effect reciprocation thereof coactive with the rotation of said supporting means, releasable wire gripping means carried by one of said shuttle members, and means engageable with said gripping means for moving said gripping means to released position.
4. A wire netting machine comprising a pair of shuttle members, means supporting said shuttle members in alinement, means for rotating said supporting means, means engageable with said shuttle members to effect reciprocation thereof coactive with the rotation of said supporting means, a wire gripping means carried by one of said shuttle members, and means engageable with said gripping means at the end of each stroke of said one shuttle member for moving said gripping means to released position.

5. A wire net forming machine comprising a pair of shuttle members, means supporting said shuttle members in alinement, means for rotating said supporting means, means engageable with said shuttle members to effect reciprocation thereof coactive with the rotation of said supporting means, a wire tensioning means car-

ried by one of said shuttle members, gripping means carried by the other of said shuttle members, and means engageable with said gripping means at the end of each stroke of said other shuttle member for moving said gripping means to released position.

5 6. A wire net forming machine comprising a pair of spaced drum members, means for rotating said drum members in unison, opposed shuttle members carried by each of said drum members, and means for reciprocating said shuttle members coactive with the rotation of said drum members.

10 7. A wire net forming machine comprising a pair of spaced apart drum members, means for rotating said drum members in unison, opposed shuttle members slidably carried by said drum members, and stationary cam means engageable with said shuttle members to effect reciprocation of said shuttle members coactive with the rotation thereof.

15 8. A wire net forming machine comprising a drive shaft, a pair of spaced apart drum members fixedly secured to said drive shaft, opposed

shuttle members slidably carried by said drum members, means for reciprocating said shuttle members coactive with the rotation thereof, and a welding means disposed between said drum members.

5 9. A wire net forming machine comprising a drive shaft, a pair of spaced apart drum members secured to said drive shaft, guide means carried by each of said drum members in parallel relation to said drive shaft, opposed shuttle members slideable in said guide means, and means for reciprocating said shuttle members coactive with the rotation of said drum members.

10 10. A wire net forming machine, comprising in combination, means for stretching the warp strands horizontally in spaced relation, means for laying the weft strands across the upper sides of the warp strands, means for welding the weft strands on the warp strands, and tension means operable on the weft strands during the welding of said weft strands on the warp strands.

15 20 THEODOR RÖSSLER.
